CLAIM

The ornamental design for a data cartridge memory reader, as shown and described.

DESCRIPTION

FIG. 1 is a perspective top view of the data cartridge memory reader.

FIG. 2 is a front view thereof;

FIG. 3 is a rear view;

FIG. 4 is a top view; and,

FIG. 5 is a left side view of the invention, the right side being the mirror image.

The device includes a plain and unornamented bottom, which is not shown.

The broken lines in the drawings indicate unclaimed portions of the data cartridge memory reader and form no part of the claimed design.
